COMBINED TAP AND LIQUID DISPENSER

Virgil L. Purviance, 122 Edmund Road, Hollywood, Fla.

Filed Apr. 3, 1962, Ser. No. 69,566

Term of patent 7 years

(Cl. D58—26)

FIG. 1

FIG. 2

FIG. 3

FIG. 4

FIG. 5

FIGURE 1 is a top plan view of a combined tap and liquid dispenser, embodying my new design;

FIGURE 2 is a side elevational view;

FIGURE 3 is a bottom plan view;

FIGURE 4 is an end view looking from the left of FIG. 1; and

FIGURE 5 is an end view looking from the right of FIG. 1.

I claim:

The ornamental design for a combined tap and liquid dispenser, as shown.
